UNITED STATES PATENT OFFICE.

FRANCIS A. BELL, OF BARDUE, WEST VIRGINIA.

DEVICE FOR SIDE-DRESSING SAWS.

SPECIFICATION forming part of Letters Patent No. 723,810, dated March 31, 1903.

Application filed July 5, 1902. Serial No. 114,423. (No model.)

To all whom it may concern:

Be it known that I, FRANCIS A. BELL, a citizen of the United States of America, residing at Bardue, in the county of Jefferson and State 5 of West Virginia, have invented certain new and useful Improvements in Devices for Side-Dressing Saws, of which the following is a specification.

This invention relates to saw-sharpening devices, and particularly to that class known as "saw-files," this invention being designed for side-filing the outer surfaces of the teeth in order that the set of the outer surfaces may be uniform in order to produce a smooth cut 15 from ridges or marks of the teeth.

The object of the invention is to produce a device of the character noted which is readily applied by the operator and which may be held in place by the operator during the manipulation of the file. Furthermore, the object of the invention is to produce means for adjusting the position of the file with relation to the saw and for insuring a uniform action on all of the teeth.

25 A further object of the invention is to produce a file-carrying block having a handle with means for limiting inward movement of the block and the depth of the cut of the file.

Finally, the object of the invention is to produce a side file which will prove simple in construction, efficient and satisfactory in use, and comparatively inexpensive to produce and sustain.

With the foregoing and other objects in view the invention consists in the details of construction and in the arrangement and combination of parts to be hereinafter more fully set forth and claimed.

In describing the invention in detail reference will be had to the accompanying drawings, forming part of the specification, wherein like characters denote corresponding parts in both views, and in which—

Figure 1 is a perspective view representing the invention applied to a saw. Fig. 2 is a longitudinal view representing the invention in section.

In the drawings, 1 indicates the base or body of the device, having a series of adjustable gage-posts 2, which posts are provided with scales in order that they may be set to the same relative position without the exer-

cise of undue care. I prefer to employ a jam-nut 3 to secure the posts at varying degrees of adjustment, though in practice this may 55 be dispensed with. The body is provided near its end beyond the posts with a dovetail groove 4 for the reciprocating block, said block having a seat 5 for the reception of a file-blade 6, which file-blade is of greater 60 thickness than the depth of the seat in order that said blade will project beyond the surface of the block. The body is provided with a slot 7, which intersects with the dovetail groove approximately centrally the width of 65 the groove, said slot terminating a suitable distance from each side of the body. A shank 8 is formed with or attached to the block and is slidable in the slot of the body. A handle 9 is formed with or attached to a shank, and 70 the shank is of a greater length than the thickness of the body from the recess to the outer surface. The handle is made to form shoulders 10 at its junction with the shank, and thus a certain amount of space is left between the shoulders and the outer surface of 75 the body.

In operation the posts are seated against the side of the saw, and the block is reciprocated by the handle, so that the tooth acted 80 upon is cut away until the shoulders of the handle contact with the outer surface of the body. When each tooth has been acted upon in a manner stated, it will follow that they will have a set which will result in a smooth 85 cut. The relation of the block to the dovetail groove is such as to permit a limited movement in order that the block may approach the saw until the shoulders of the handle engage the body. The posts of the 90 base are held against the saw by the hand of the operator or in any other manner desired.

The construction, operation, and advantages, it is thought, will be understood from the foregoing description, it being noted that 95 various changes may be made in the proportions and details of construction without departing from the scope of the invention.

Having fully described my invention, what I claim as new, and desire to secure by Letters 100 Patent, is—

1. In a device of the character described, a base having a dovetail groove and a slot, posts adjustable in the base, a block having

a handle with its shank slidable in the slot, a file carried by the block as and for the purpose specified.

2. In a device of the character described, 5 a base having a groove and forming a guide and a slot extending transversely the base, posts adjustable in the base, a block reciprocating in the groove, a handle having a shank slidable in the slot and means for limiting 10 the inward movement of the handle and a file

carried by the block substantially as described.

In testimony whereof I affix my signature, in the presence of two witnesses, this 30th day of June, 1902.

FRANCIS A. BELL.
